United States Patent Office

Des. 212,085

Patented Aug. 27, 1968

212,085

HEADREST

William S. Fulkerson, and Rose Marie E. Fulkerson, both of 2917 Hunt Drive, Rancho Cordova, Calif. 95670

Filed Dec. 20, 1966, Ser. No. 5,126

Term of patent 7 years

(Cl. D15—8)

FIG. 1

FIG. 3

We claim:

The ornamental design for a headrest, substantially as shown.
